MEANS FOR SECURING A CANVAS TO A FRAME

Carroll E. Thomas, Oakland, Calif.

Application July 24, 1945, Serial No. 606,758

4 Claims. (Cl. 45—130)

1

This invention relates to improvements in artists' equipment, and more particularly to novel means for mounting a canvas, fabric or paper sheet, on a rectangular frame.

An object of my invention is to provide novel means for securely mounting a canvas on a supporting frame.

Another object of my invention is to provide novel means for quickly securing a canvas to a rectangular supporting frame the said means embodying a construction whereby the canvas may be securely held in a taut position without the use of tacks or other independent means.

A further object of my invention is to provide artists' equipment of the kind characterized, embody novel means by which a canvas may be readily mounted on a supporting frame and securely held thereon while its outer surface is painted by an artist, and which permits the subsequent tacking of the canvas to the frame for permanent mounting.

Other and further objects of my invention will be pointed out hereinafter, or will be indicated in the appended claims, or will be obvious to one skilled in the art upon an understanding of the present disclosure. For the purpose of this application I have elected to show herein certain forms and details of means for mounting an artist's canvas on a rectangular frame representative of my invention. It is to be understood, however, that the embodiment of my invention herein shown and described is for the purpose of illustration only and that therefore it is not to be regarded as exhaustive of the variations of the invention, nor is it to be given an interpretation such as might have the effect of limiting the claims, short of the true and most comprehensive scope of the invention in the art.

In the accompanying drawings:

Fig. 1 is a top plan view showing an artist's canvas mounted on a rectangular frame by means of the present invention;

Fig. 2 is a bottom plan view of the same;

Fig. 3 is an enlarged longitudinal sectional view of the same;

Fig. 4 is a perspective view of a fragmentary part of one of the clamping members; and

Fig. 5 is a perspective view of another fragmentary part of the clamping member.

Referring to the drawings, the numeral 1 designates the side members of an open rectangular frame which is commonly used to support an artist's canvas, fabric or paper sheet, 2. Heretofore, it has been the common practice for artists to secure the turned back edges of a canvas

2

to a frame by means of closely spaced tacks which were driven through the canvas and into the edges of the frame at each of the four sides of the latter. It ordinarily takes considerable time and effort to properly attach a canvas to a frame by the common method now used, and it likewise requires considerable time to remove the tacks when the canvas is detached from the frame. By means of the present invention a canvas may be quickly secured to and detached from a supporting frame.

The frame members 1 are suitably interlocked at their engaging ends, and corner wedges 3 are commonly used to spread the said members and thereby enlarge the frame to suitably maintain the canvas in a taut position.

The present invention comprises two pair of angle irons or members 4 and 5 which preferably are slightly shorter than the length of the side members 1 of the frame with which they normally engage. Each of the angle members 4 and 5 are formed with longitudinally disposed sides 6 and 7 which are arranged at substantially right angles with respect to one another. The sides 6 of the angle members normally engage with the edge portions of the canvas extending over the side edges of the frame, and the sides 7 normally engage with the frame's rear side. The longitudinal edges of the sides 7 of each of the angle members 4 and 5 are bent inwardly and outwardly to provide a reinforcing strip 7', the said strip constituting a fastening member 7a where the side 7 is cut away midway between its ends, as at 7b, for anchoring an end of the clamping member 8.

The sides 6 of each of the angle members are formed at spaced intervals along their lengths with pointed punched out tongues 6', or other sharp projecting members, which are adapted to extend through the canvas and penetrate the side edges of the frame when the angle members are applied to the latter. The sides 6 of each of the angle members are suitably cut away at spaced intervals along their outer edges to provide openings 6a for the applying of tacks or other securing means for the permanent attachment of the canvas to the frame, if so desired.

Each of the opposed pair of angle members 4 and 5 are urged toward each other by spring actuated clamping members 8 which may assume any one of a number of different forms. In the particular embodiment shown in the drawings, the clamping members each comprise elongated flat bars 9 having their inner ends connected to a helical spring 10 and their outer ends formed

with suitable means for detachably engaging with a fastening member 7a of the angle members. The elongated bars 9 have substantially the same thickness as the sides 7, thereby permitting them to lie in the same plane as the said sides when attached to the latter. The helical springs 10, in cross section, preferably have a somewhat rectangular shape, rather than being circular.

When the angle members 4 and 5 are brought into firm engagement with the turned back edge portions of the canvas, the pointed tongues 6' of the sides 6 project through the said canvas and penetrate the side edges of the frame, thereby preventing the slipping of the edge portions of the canvas with respect to the said side edges of the frame. The spring actuated clamping members 8 each exert an inward pressure on their respective pair of angle members 4 and 5, thereby causing the sides 7 of the latter to firmly engage with the turned back edge portions of the canvas and remain in such positions until they are subsequently detached.

In the event the canvas is to be permanently secured to the frame prior to the detachment of the angle members, suitable tacks may be driven through the turned back edge portions of the canvas and into the frame at points where the openings 6a in the sides 6 occur.

It is apparent that the present invention may be adapted for use with respect to frames of different shapes by changing the general shapes of the angle members 4 and 5 so they conform to and fit upon the sides of the frame with which they are used.

What I claim is:

1. In means for securing a sheet to a frame, pairs of opposed elongated angle members substantially L-shaped in cross section arranged for engagement with the sheet where it is extended over the side edges of the frame and also with the rear side of the frame, the said angle members being independently adjustable, and spring clamp means connected to and positioned between the elongated members of each pair, whereby the said members of each pair are urged toward one another to firmly engage with the sheet and clamp it against the edges of the frame.

2. In means for securing a canvas to a frame, pairs of opposed elongated unconnected and independently adjustable angle members arranged for engagement with the canvas where it is extended over the side edges of the frame, pointed means carried by the angle members for penetrating the canvas and the side edges of the frame whereby the canvas is normally prevented from slipping with respect to the side edges of the frame, and spring clamp means connected

to and positioned between the elongated members of each pair, whereby the said members of each pair are urged toward each other to maintain the said members in positions so the pointed means carried thereby remain in penetrating engagement with the canvas and the frame.

3. In means for securing a sheet to a frame, pairs of opposed elongated angle members arranged for engagement with the sheet where it is extended over the side edges of the frame, pointed means carried by the angle members for penetrating the sheet and the side edges of the frame, whereby the sheet is normally prevented from slipping with respect to the side edges of the frame, and spring clamp means connected to and positioned between the elongated members of each pair, whereby the said members of each pair are urged toward each other to maintain the said members in positions so the pointed means carried thereby remain in penetrating engagement with the sheet and the frame, the said angle members having spaced openings arranged therein for the insertion of tacks for the permanent securing of the sheet to the frame when the angle members are removed.

4. In means for securing a sheet to a frame, pairs of opposed elongated members arranged for engagement with the sheet where it is extended over the side edges of the frame, the said elongated members having spaced openings arranged along their lengths for permitting the driving of independent pointed members through the sheet and into the frame for the permanent attachment of the sheet to the frame, and spring clamp means connected to and positioned between the elongated members of each pair, whereby the said members of each pair are urged toward one another to firmly engage with the sheet and clamp it against the edges of the frame.
